UNITED STATES PATENT OFFICE.

HERMAN J. BUCK, OF ELLWOOD CITY, PENNSYLVANIA, ASSIGNOR TO MATHEWS
GRAVITY CARRIER COMPANY, OF ELLWOOD CITY, PENNSYLVANIA, A COR-
PORATION.

STRAIGHT-LIFT ELEVATOR.

1,248,069.

Specification of Letters Patent. Patented Nov. 27, 1917.

Application filed February 3, 1914. Serial No. 816,143.

To all whom it may concern:

Be it known that I, HERMAN J. BUCK, citizen of the United States, resident of Ellwood City, county of Lawrence, State of Pennsylvania, have invented certain new and useful Improvements in Straight-Lift Elevators, of which the following is a specification.

My invention relates to straight lift elevators for handling merchandise of various kinds and particularly to the carriage on which the merchandise is placed.

The object of my invention is to provide means for holding the carriage in a horizontal position while it is passing over the top of the elevator or from the up to the down side.

Other objects of the invention will appear from the following detailed description.

The invention consists generally in various constructions and combinations, all as hereinafter described and particularly pointed out in the claims.

In the accompanying drawings forming part of this specification,

Figure 1 is a sectional view of the upper portion of a straight lift elevator embodying my invention,

Fig. 2 is a vertical sectional view, illustrating the means for mounting the carriage in the elevator and the driving mechanism therefor,

Fig. 3 is a sectional view on the line $\alpha-\alpha$ of Fig. 1.

In the drawing, 2 represents an upright frame having bearings at the top for a shaft 3. Sprocket wheels 4 are mounted on the shaft 3 for the sprocket chains or belts 5, similar wheels being provided at the bottom of the elevator, not shown. A gear wheel 6 is mounted on the shaft 3 and meshes with a pinion 7 on a drive shaft 8 that is provided with a driving pulley 9. The carriage consists preferably of a bar 10, preferably in

the form of an inverted T-rail, provided at each end with hanger arms 11 pivotally connected at 12 to the sprocket chains or belts of the elevator. In practice, a series of these carriages are mounted on the belts but for clearness of illustration I have only shown one of them, the others being substantially the same in construction and operation. The bars 13 are mounted transversely of the bar 10 and secured thereto and have

upper surfaces on which the articles or packages of merchandise to be transported are placed.

On the underside of one of these bars 13 and beneath the cross bar 10 of the carriage, I provide a gear segment 14 having teeth to mesh with the teeth of a pinion 15 mounted on the shaft 3, said pinion in turn meshing with a gear 16 on a shaft 17 that is driven through a pinion 18 and a gear 19 secured on the hub of the sprocket wheel 4. This arrangement of gearing allows for the desired speed of operation of the pinion 15 to move the lower portion of the carriage across the elevator from one side to the other commensurate with the travel of the pivots of the carriage on the belts, the object being to maintain the carriage in a horizontal position during such movement and prevent it from tilting or swinging with the attendant danger of dislodging the packages thereon. The pinion is loosely mounted on the shaft 3 and is driven at a greater speed than said shaft. This speed of operation will be varied to suit different elevators and the travel of the carriages.

The hanger arms move upward between the vertical guides 20, the inner guide being curved inwardly at its upper end, as indicated at Fig. 1. The guiding action of the outer upright guide ceases at the point 35 where the curvature begins and a supplementary or auxiliary guide 21 is provided to bear upon the upper edge of the cross bar 10, thereby holding the carriage in a horizontal position until it passes out from between the guides. In Fig. 1 the cross bar or T-rail is shown in the position it occupies just before it passes out of engagement with the guides. The opposite or down side of the elevator is provided with guides 20' and 21' corresponding to those on the up sides of the elevator.

In the operation of the device, the carriage passes upwardly between the vertical guides and upon reaching the curved portions thereof, is directed inwardly, being held in its horizontal position by the engagement of the guides 21 with the T-shaped cross bar 10. At the time the cross bar passes out of contact with the guides, the gear segment will engage the pinion 15, driven through the gear mechanism described, and will remain in mesh with the

segment until the T-shaped cross bar of the carriage passes between the guides on the opposite or down side of the elevator.

While this takes place, the platform of the carriage will be moved from the up side of the elevator to the down side thereof, the surface of the carriage being held in a substantially horizontal position during such movement.

10 I claim as my invention:

1. In a straight lift elevator, the combination with a drive shaft having wheels thereon, elevating belts passing over said wheels, a carriage suspended from said belts, and a transverse gear segment on the lower side of the carriage, of a gear on the said shaft with which said segment is engaged as the carriage passes from one side of the elevator to the other, and means for operating said gear at a speed proportionate to the speed of the belt-carrying wheels.

2. In a straight lift elevator, the combination with a drive shaft having wheels thereon, elevating belts passing over said wheels, a carriage suspended at opposite sides from said belts, and a transverse gear segment on the lower side of the carriage between the

ends thereof, of a gear between the ends of said drive shaft with which said segment is engaged as the carriage passes from one side 30 of the elevator to the other, and means for operating said gear at a speed proportionate to that of the drive shaft.

3. In a straight lift elevator, the combination with a drive shaft having wheels thereon, elevating belts passing over said wheels, a carriage suspended from said belts, pairs of vertically disposed guideways engaged by the lower outer portions of the carriage and curved inwardly at their upper ends, a 40 transverse gear segment on the lower side of the carriage between the ends thereof, of a gear on the drive shaft intermediate its ends with which gear said segment is adapted to engage as the carriage crosses from one set 45 of guides to the other, and means for operating said gear at a speed proportionate to the speed of the belt-carrying wheels.

In witness whereof, I have hereunto set my hand this 20th day of January, 1914.

HERMAN J. BUCK.
